VARIABLE SIGN

Lewis S. Murphy, Marion, Ind., assignor to Chicago Railway Equipment Company, Chicago, Ill., a corporation of Illinois

Application June 19, 1933, Serial No. 676,445

11 Claims. (Cl. 40—130)

This invention relates to signs and particularly to traffic markers for indicating curves, fences, posts, bridge abutments, railroad crossing gates and targets, and other objects along the highway ways.

An important object of the invention is to provide a simple, inexpensive sign device which may be purchased and stocked by highway or railroad officials in standard shapes and which may be readily assembled in the field according to the particular object to be marked.

Another object of the invention is to provide a sign unit arranged to be assembled with other similar units in various numbers to form a variety of designs.

These objects and others hereafter appearing are attained substantially by the devices illustrated in the accompanying drawings showing signs arranged in conspicuous designs formed with units of more or less standard shapes. Each unit has a plurality of pocketed projections forming seats for reflecting lenses, or lamps, or other visible indicating means, and a recess or perforation shaped to snugly fit over a pocketed projection of another similar unit to assemble the units together.

Figure 1 is a plan view of a sign unit illustrating the invention.

Figure 2 is a side view of the same.

Figure 3 is a view of a slightly modified sign unit.

Figure 4 is a plan view of an assembled sign including the units in Figures 1 and 3.

Figure 5 is a side view of another form of unit.

Figure 6 is a plan view of a sign formed of a pair of units similar to that in Figure 5.

Figure 7 is a longitudinal section taken on the line 7—7 of Figure 6.

Figures 8, 10, and 11 are views of other sign arrangements.

Figure 9 is a section on the line 9—9 of Figure 8.

Figure 12 shows a curved sign unit, and Figure 13 diagrammatically illustrates a particular use for the novel sign in connection with railroad grade crossings.

The sign unit in Figures 1 and 2 comprises an elongated narrow body or frame part 1 with a series of hollow cylindrical projections 2 receiving reflecting lenses 3. The center of the body part is slightly enlarged at 6 and circularly recessed at 4, the recess 4 being shaped to snugly fit over any of the pocketed projections 2 of a similar unit.

The unit 1a, shown in Figure 3, is similar to that in Figure 1 except that a central lens projection 5 replaces the central assembling recess of the former figure. Figure 4 shows the units of Figures 1, 2 and 3 assembled in the form of a cross. It will be understood that the recess 4 may be pressed over the pocket 5, or otherwise secured thereto as by soldering or other suitable means. The perforated central portion 6 of unit 1 is preferably slightly offset from the remainder of the body 1 to improve the fit and strength of the joint.

In Figure 5, the sign unit 7 has three pocketed lens projections 8 and a perforated assembling enlargement 9 at one end. The rectangular sign 15 in Figure 6 is formed of the unit 7 assembled with a unit 10 having four lens pockets 11, the end one of which is assembled with perforated enlargement 9 of unit 7, and a perforated assembling enlargement 12 at the other end in which 10 it is mounted a cup 13 whereby this enlargement is 15 adapted for mounting a lens 14 similar to that inserted in the other lens pockets. As indicated in Figure 7, each of the lenses 14 is assembled with its lens pocket by means of a ferrule 15 20 of lead or similar material inserted around the lens and upset by a circular tool.

The novel sign device may be used with electric lights, as shown in Figures 8 and 9, instead of reflecting lenses. In Figure 8, three sign units 30 16, 17 and 18, each having perforated enlargements at one end, are assembled in the form of a Y. The pocketed projections of the units, one of which is shown at 19 in Figure 9, extend rearwardly and are equipped with electric lamp 35 sockets 20 and lenses 21. Where the sign units are assembled in angular relation at angles other than 90° and 180°, the assembling enlargements are preferably aligned with the remainder of the units instead of being offset as in Figure 2.

Figure 9 illustrates the manner of assembling three units at a single connection, the end projection 19 of unit 16 being inserted through the perforated ends 22 and 23 of units 17 and 18. The assembling element 16a at the end of unit 16 may be provided with a cup, such as 13 in Figure 7, and a lamp socket.

In Figure 10, a group of units 24, similar to the units 16 and 17 in Figure 8, are assembled in 50 the form of a diamond and applied to a roadside standard 26 having a cross beam 27.

In Figure 11, a series of sign units 28, 29 and 30 are assembled in a straight line, this form being adapted for marking a fence rail, cross- 55

ing gate, or similar object extending along the road.

Figure 12 shows a curved sign unit 31 with pocketed lens projections 32 and a perforated 5 assembling enlargement 33 at one end. It will be understood that the sign unit may have a variety of shapes and may be equipped with reflecting lenses as in Figures 1 to 7, or lamps as in Figures 8 and 9, or with other visible indicating 10 means.

The various embodiments shown are merely for the purpose of illustrating different uses of the broad inventive features, and various details may be modified according to particular needs. 15 The exclusive use of all such modifications as come within the scope of the appended claims is contemplated.

What is claimed is:

1. In a sign, a plurality of units each with a 20 plurality of projecting parts forming seats for visible indicators, and a recessed part shaped to snugly interengage with any of the projecting parts of another of said units whereby said units may be assembled in various numbers and in various 25 relations.

2. In a sign, a plurality of similar units each with a plurality of pocketed projections for seating visible indicia, and a perforation shaped to snugly receive any of the projecting parts of 30 another of said units whereby said units may be assembled in various numbers and in a variety of designs.

3. A sign unit comprising an elongated bar having a series of bosses spaced substantially 35 uniformly throughout its length, most of said bosses forming mountings for luminous elements but at least one of said bosses being perforated to receive a luminous element mounting boss of a similar unit to form a built up sign structure.

4. A sign unit comprising an elongated bar having a main body portion and a restricted portion offset from the plane of said body portion, a series of mountings for luminous units along 40 said bar, said offset portion being perforated to receive a corresponding mounting on the body of a cooperating unit whereby the body portions of both units may lie in the same plane.

5. A sign unit comprising an elongated narrow bar with a restricted portion enlarged in width 45 and having an opening corresponding in diameter to the normal width of the bar, a series of luminous unit mountings on said bar correspond-

ing in outside diameter to the width of said bar any one of which may be inserted in the corresponding opening of another unit to form an assembled sign structure.

6. In a sign structure, an elongated bar having a portion offset from the plane of the remainder of the bar, and having a plurality of luminous units disposed at intervals along its length at the side of said offset portion, another elongated bar having a plurality of luminous 10 units disposed at intervals throughout its length one of which projects through said offset portion of the first mentioned bar.

7. In a sign, a plurality of elongated bars each having a series of luminous element mountings 15 disposed along its length, said bars being assembled by the insertion of a mounting of one bar through an opening in the other bar whereby the referred to mounting on the first-mentioned bar forms a unit of the series of luminous 20 element mountings on the other bar.

8. In a sign, a unit having a mounting and a visible indicator seated thereon, and another unit including a mounting for a visible indicator and a recess for cooperating with the referred 25 to mounting on said first-mentioned unit to secure together said units independently of said first-mentioned indicator.

9. A sign unit including a body part, a lateral projection having structure for attachment of an 30 illuminating member, and a recess shaped for snug assembly with a part of a similar sign unit corresponding to said projection to prevent separation of the units in a direction in the plane 35 of said body part.

10. In a sign, a plurality of units having visible indicia, one of said units having a lateral projection forming a lamp socket and another unit having a recess assembled with said projection so as to prevent separation of said two units trans- 40 versely of the axis of said socket.

11. In a sign, a plurality of units each including a body part, a lateral projection on one of said parts, and an illuminating member mounted on said projection, the body part of another unit 45 having a recess snugly assembled with said projection so as to secure said two units independently of said illuminating member against separation in a direction in the plane of either of said body parts.

LEWIS S. MURPHY.
